UNITED STATES PATENT OFFICE.

FRANK LEWIS AND OTTO FRIEDMAN, OF BROOKLYN, NEW YORK.

DESIGN FOR A BADGE OR SIMILAR ARTICLE.

Application filed June 19, 1926. Serial No. 18,105. Term of patent 3½ years.

To all whom it may concern:

Be it known that we, FRANK LEWIS and OTTO FRIEDMAN, citizens of the United States, and residents of New York, borough of Brooklyn, in the county of Kings and State of New York, United States of America, have invented a new, original, and ornamental Design for a Badge or Similar Article, of which the following is a specification, reference being had to the accompanying drawing, forming part thereof.

Fig. 1 is a face view of a badge embodying our new and original design.

Fig. 2 is an edge view of Fig. 1.

We claim:

The ornamental design for a badge or similar article substantially as shown.

FRANK LEWIS.
OTTO FRIEDMAN.
